UNITED STATES PATENT OFFICE

162,126

INFLATABLE TOY FIGURE OR SIMILAR ARTICLE

Alexander Burkes, New York, N. Y., assignor to Plastic Innovations, Inc., New York, N. Y., a corporation of New York

Application December 13, 1949, Serial No. 6,585

Term of patent 7 years

(Cl. D34—15)

To all whom it may concern:

Be it known that I, Alexander Burkes, a citizen of the United States, residing at New York, in the county of New York and State of New York, have invented a new, original, and ornamental Design for an Inflatable Toy Figure or Similar Article, of which the following is a specification, reference being had to the accompanying drawing, forming part thereof.

In the drawing

Fig. 1 is a side elevational view of an inflatable toy figure or similar article, showing my new design;

Fig. 2 is a top view thereof; and

Fig. 3 is a front view thereof.

I claim:

The ornamental design for an inflatable toy figure or similar article, substantially as shown.
ALEXANDER BURKES.
